TRAFFIC MARKER

James R. Elliott, Port Huron, Mich.

Application March 3, 1941, Serial No. 381,423

2 Claims.

(Cl. 94—1.5)

This invention relates to improvements in traffic markers adapted to be positioned at street intersections, crosswalks, safety lanes, or lines for defining or marking the middle of a roadway or elsewhere to guide or direct drivers of vehicles, pedestrians, and others in order to prevent or diminish the liability of road accidents by the vehicles traveling in opposite or different directions and to avoid accidents to pedestrians and others.

The invention is equally adaptable for marking and defining restricted parking areas, tennis court, etc.

One of the prime objects of the invention is to design a marker which can be embedded in a plastic body of bituminous, cementitious, and other forms of plastic pavements.

Another object is to design a simple, practical, and substantial marker which can be firmly anchored in position; which will not creep; which has a cap or insert colored in contrast to the pavement, but which will endure the severe traffic conditions incident to the pounding thereon and the skidding and sliding of vehicle tires thereover, without appreciable wear or loss of its distinguishing color.

A further object is to design a traffic marker comprising a metal frame having a hard, color-fast cap or insert of stone hardness which will not crack, chip, or otherwise deteriorate when exposed to heavy traffic, and which will be securely anchored in said frame.

A further object still is to provide a traffic marker which may be inserted at the time the pavement is laid or subsequent thereto, and which can be firmly anchored in position.

With the above and other objects in view, the present invention consists in the combination and arrangement of parts, hereinafter more fully described, illustrated in the accompanying drawings, and more particularly pointed out in the appended claims, it being understood that changes may be made in the form, size, proportions and minor details of construction, without departing from the spirit, or sacrificing any of the advantages of the invention.

In the drawings:

Fig. 1 is a side elevational view of a button type of marker;

Fig. 2 is a top plan view thereof;

Fig. 3 is a sectional side elevational view;

Fig. 4 is an inverted plan view;

Fig. 5 is a sectional side view showing the marker and mold, with the marker in inverted position;

Fig. 6 is an end elevational view showing a center line marker;

Fig. 7 is a top plan view thereof;

Fig. 8 is a transverse sectional view taken on the line 8—8 of Fig. 7;

Fig. 9 is an inverted plan view; and,

Fig. 10 is a fragmentary view similar to Fig. 7 and showing a slightly different construction and in which an expansion pin or bolt is used as the anchoring means.

Various forms of surface arrangement can be made to secure the desired result, as it will be obvious that the markers can be arranged in lines to define traffic lanes, center lines, or safety zones, or they can be arranged to spell out various words such as "Stop," "Right," "Left," etc.

The invention is typified by two specific embodiments showing how the invention may be carried into effect. These are similar, the only substantial difference being in the shape, one of which is a round button type, while the other is rectangular in shape.

Referring now more particularly to Figs. 1 to 5 inclusive of the drawings, in which I have shown a button type marker such as used to define safety zones and traffic lines, each marker comprising a body portion 10, preferably, but not necessarily, constructed of brass or similar material. This button is formed with a convex upper face and is provided with a relatively large pocket or depression 11 defined by the shoulder 12 which is concentric to the periphery of the body portion 10. A centrally disposed opening 13 is provided in the body portion 10, and a hollow shank or tube member 14 is mounted therein, the inner end of the tube being flared or tapered so that it can be readily secured in position and also assist in securing the insert in the pocket. An opening 15 is provided adjacent the outer end of the tube 14 and for a purpose to be presently described.

The material of which the base or body portion of the marker is formed is of approximately uniform thickness. It can be either cast or stamped as desired, the upwardly curved edge 16, together with the rim or shoulder 12, forming a circumferential groove 17 in the bottom portion of the base, and this groove is of prime importance, as it serves to form an anchor for anchoring the marker in the pavement, and counteracting the "push" caused by the application of brakes or skidding and sliding of automobiles and vehicles while traveling over these markers.

The pocket 11 is filled with a special compound C suitably colored for the purpose intended, and this is primarily in the form of a powder which

when mixed with a liquid, forms a mass of proper consistency so that it readily flows.

In the manufacture of the marker buttons, I find it advantageous to provide a rubber mold M (see Fig. 5), the face of which is concave as shown at 18, this curvature being uniform so that the completed button, shown in inverted position in the mold, will have a convex upper face without creases or other irregularities, thus eliminating any machining or finishing.

In practice the base or frame is first inverted and placed in the mold, as clearly shown in Fig. 5 of the drawings. The mixture C is then poured through the tube 14, which serves as a funnel, to completely fill the pocket, the air escaping through a plurality of openings 19 provided as shown, the air in the tube escaping through the opening 15 previously referred to. When the pocket is filled, the material is left to "set," and the marker is then complete and ready for installation.

Upon installation in a pavement, the bituminous or cementitious material enters the tube 14 through the open lower end and through the opening 15 so that the marker will be firmly and securely anchored.

In Figs. 6 to 10 inclusive, I have shown a center line marker, and this is formed substantially the same as the button type with the exception that the frame 20 is rectangular in shape, the edges being beveled as at 21, said edges terminating in a vertical marginal rim 22, which rim defines the pocket or space in which the compound C is placed, the lower edge of the rim extending horizontally a predetermined distance as shown at 23. A longitudinally disposed bar 24 is cast integral with or secured to the rim 23, and transversely disposed bar sections 25 span the frame as clearly shown in Fig. 9 of the drawings.

The space between the beveled edges 21 and the rim 22 provides a continuous groove 26 in the bottom face of the marker, and this groove serves the same purpose as the groove 17 hereinbefore described. Bolts 27 are provided in the bar 24 and at the opposite ends thereof, these bolts being threaded to accommodate nuts 28 as usual, said bolts extending downwardly into the bituminous or cementitious pavement for anchoring the marker in position.

The center section or pocket of this center line marker is filled in substantially the same manner as is the button type, a rubber mold (not shown), of proper size and shape being provided, and the marker is placed face down thereon, after which the compound C is poured into the pocket until the compound is flush with the lower edge of the bars, the rim 23 and the open spaces

between the bar sections 24 and 25 serving to anchor the insert in the frame.

The rubber mold provides for uniform shape and a smooth clear surface and the compound does not cling or hang thereto.

It will, of course, be obvious that the marker can be of any desired shape, and that lag screws can be substituted for the bolts if desired, in fact I find it advantageous to use the bolts 27 with companion nuts 28 where the markers are inserted when the road is being built. When installing in pavements already constructed, I prefer to use the marker shown in Fig. 10. It is merely necessary to bore holes of suitable size in the pavement in proper relation, then fill them with a suitable compound which bonds with the concrete, and lag screws (not shown), can be inserted through the openings 29 and forced into this compound to anchor the marker in position, the body 20 being countersunk as at 30 to accommodate the head of the screw.

From the foregoing description, it will be obvious that I have perfected a very simple, practical, and effective marker for defining center lines, safety zones, etc., for vehicles and pedestrians which can be readily manufactured and assembled, and which can be easily located and anchored in position.

What I claim is:

1. A traffic marker comprising a metallic frame having upwardly extending side walls terminating in a centrally disposed pocket, a plurality of openings in the bottom wall of said pocket and a centrally disposed hollow tubular member having a flared upper end mounted in said bottom wall and projecting a predetermined distance into said pocket, said flared end serving to secure the member in the frame and also as a funnel to admit the mixed compound to the pocket, the lower end serving also as an anchor for securing the frame in a pavement.

2. A traffic marker comprising a cast frame formed with upwardly extending side walls terminating in a centrally disposed pocket adapted to accommodate a cast compound insert, an independent hollow tubular member mounted in the bottom wall of the pocket and formed with a flared upper end projecting a predetermined distance thereinto to secure the member in position, said member being provided with an air vent spaced from the lower end thereof, and also serving as a funnel to permit filling said pocket with the compound the lower end serving as an anchor for securing the frame in the pavement, and a groove between the outer rim of the frame and the pocket to prevent "push" of the marker in a pavement.

JAMES R. ELLIOTT.
